UNITED STATES PATENT OFFICE.

CHARLES J. JACKSON, OF ERIE, PENNSYLVANIA, ASSIGNOR, BY MESNE ASSIGNMENTS, TO REUBEN G. WRIGHT, OF WESTFIELD, NEW YORK.

SCREW-CUTTING DIE.

SPECIFICATION forming part of Letters Patent No. 707,233, dated August 19, 1902.

Application filed October 5, 1900. Serial No. 32,112. (No model.)

To all whom it may concern:

Be it known that I, CHARLES J. JACKSON, a citizen of the United States, residing at Erie, in the county of Erie and State of Pennsylvania, have invented certain new and useful Improvements in Screw-Cutting Dies; and I do hereby declare the following to be a full, clear, and exact description of the invention, such as will enable others skilled in the art to which it appertains to make and use the same.

This invention relates to screw-cutting dies, and it consists in certain improvements in the construction thereof, as will be hereinafter fully described, and pointed out in the claim.

The invention is illustrated in the accompanying drawings, as follows:

Figure 1 shows a side elevation of the die. Fig. 2 shows a section on the line 22 in Fig. 1.

A marks the die-plate; B, the chasers. In the manufacture of these the chasers are placed in the molds and are secured in place as the plate A is cast. The chasers are afterward cut and ground as desired. Die-plates of this general construction have been heretofore made—that is, the chasers have been secured in the plate as the plates were cast. As far as I am aware, however, with all such constructions the faces of the chasers have been at right angles to the face of the plate A. With my construction I have placed the chasers at right angles to the plate A, so that the front edges of the thread-cutting teeth are slightly in advance of the rear edges. This gives a clearance to the cutting edge. Most pipes and other articles which are to be screw-threaded are of more or less uneven surface. Usually small ribs are formed in the process of manufacturing pipes and rods.

These ribs are usually parallel with the axis of the pipe or rod. By placing the chasers B at a slight inclination the different teeth strike the ribs at different times—that is, the chaser does not present a square shoulder to a rib, and consequently a more even cutting action is produced.

As a further improvement of my invention I have formed the plate A with the portion a immediately in advance of the chaser of greater depth than that a' immediately at the rear of the chaser. The portion a (cut away) gives clearance for the passage of chips, and the shoulder or portion a' braces the chaser, so as to prevent its spring. 55

In a cast die, as shown, the shoulder a' forms a body of metal adjacent to the chaser, and consequently as the die is tempered holds the heat in this portion of the chaser for a longer period than the cutting-face, and thus 60 gives to that portion of the chaser less temper than at the cutting edge, so that while the clearance remains sufficient this shoulder not only braces the chaser, but gives to that part of the chaser receiving the strain greater 65 strength than it otherwise would have.

What I claim as new is—

In a screw-cutting die, the combination of the cast die-plate A having depressions and shoulders, and the chasers B cast therein having their cutting-faces arranged next to the depressions and the opposite faces against the shoulders. 70

In testimony whereof I affix my signature in presence of two witnesses.

CHARLES J. JACKSON.
